UNITED STATES PATENT OFFICE.

VICTOR R. KOONTZ, OF WAYNESBORO, PENNSYLVANIA.

DIE-HEAD.

1,212,508.

Specification of Letters Patent. Patented Jan. 16, 1917.

Application filed December 12, 1914. Serial No. 876,963.

To all whom it may concern:

Be it known that I, VICTOR R. KOONTZ, a citizen of the United States, residing at Waynesboro, Pennsylvania, have invented a 5 new and useful Improvement in Die-Heads, of which the following is a specification.

My invention relates to die heads for cutting machines and the like, and the primary object thereof is the provision of a 10 construction of the kind mentioned, which has great facility of adjustment and operation under a wide range of working conditions.

A further object of my invention is the 15 provision of a die head in which the size of the die can be adjusted while the die head is in motion, whereby the workman can change quickly from one size of stock to another, without being first required to shut off the 20 power and stop the machine.

A still further object of my invention is the provision of a die head by which chasers or cutters are so supported that they can be simultaneously oscillated to open or close 25 the die, regardless of whether the die head is stationary or in motion, and in which the chasers or cutters can also be independently adjusted to the required extent.

The above and other objects of my invention 30 are set forth in the following specification taken in connection with the accompanying drawings, which illustrate a preferred embodiment of my invention, the same characters of reference being used to 35 indicate the same parts in all views.

On said drawings Figure 1 is a side elevation of my improved die head, partly in section, showing the same mounted in operative position. Fig. 2 is a front elevation of the 40 same, partly in section. Fig. 3 is a side elevation, partly in section, of one of the carriers by which the chasers or cutters are mounted in the die head. Fig. 4 is a section on the line 4—4 in Fig. 3. Fig. 5 is a section on the line 5—5 in Fig. 3. Fig. 6 is a side elevation of a modified form of carrier. Fig. 7 is an end elevation of the construction shown in Fig. 6.

In the particular description of my invention, as shown in the drawings, I employ 50 the numeral 1 to indicate the body of the die which is adapted to be secured to a suitable member for rotating the same, such as shaft 2. This shaft is supported in one or 55 more suitable bearings indicated at 3 on the framework 4 of the machine of which

my die head forms part, and the die head will have a central bore 5 which receives the stock upon which the die head operates. The body 1 supports a suitable number of 60 carriers 6 for the cutters or chasers, these carriers being shown as four in number, but obviously I may use as many or as few as desired. Each of said carriers 6 is shaped to support a chaser in its outer end and it 65 comprises an extension 7, adapted to be joined to a cylindrical section 8, which constitutes the inner end of the carrier and is adapted to be inserted into a cylindrical bore 9 in the body 1. These bores extend 70 from the front end of the body parallel to the axis of the shaft 2, almost to the rear end of the body 1, and they are, of course, equidistant from the center of the bore 5. The chasers or cutters are indicated at 10, 75 and as shown on the drawings, they comprise triangular, longitudinally extending, parallel threads, terminating in sharp points at the beveled working ends of the chasers or cutters adjacent center of the body 1. 80 These chasers are located so that they are substantially tangential with respect to the stock which is to be worked, as will be readily understood, and I provide for the simultaneous adjustment of the carriers 6 in their 85 respective bores 9 so that the size of the die can be changed or the die opened and closed, regardless of whether the body 1 is in motion or at rest, and at the same time, mount the chasers 10 so that they can be independently 90 adjusted in a manner that I shall now fully set forth.

The extension 7 of each carrier 6 has a circumferential groove 11 to receive a ball 12. The balls 12 are held in their places by 95 means of screws 13, which are set in threaded apertures 14, extending into the body 1 from the circumference thereof, these threaded bores 13 being of course the same in number as the carriers 6. The inner ends 100 of the screws 13 will have hemispherical sockets to receive the balls 12 and the grooves 11 will of course correspond in shape to the balls, so that, when the carriers are inserted into the bores, and the screws 13 with the 105 balls 12 at their inner ends turned up, the carriers will be firmly locked in the body 1 and held against longitudinal movement, but, at the same time, will be free to rotate when actuated in the necessary manner. In order to actuate the carriers, I provide 110 devices which encircle the body 1 and

engage all of the carriers 6, so that when the devices in question are operated, the carriers are turned simultaneously in the bores 9 through equal degrees of arc.

5 For the purpose of mounting the actuating devices above mentioned, as required to produce the desired result, I provide the body 1 with a number of slots 15 in its circumferential surface. These slots are the 10 same in number as the bores 9, and are so placed as to constitute openings of these bores through the sides of the body, being so located that they open into the bores 9 through the portions which are farthest 15 from the central bore 5. The bores 15 are better shown in Figs. 1 and 2, and I encircle the body with a ring 16 having internal projections 17 which pass into the slots 15 and have threaded openings to receive 20 screws 18 similar to the screws 13. The screws 18 have hemispherical sockets at their inner ends to accommodate balls 19, and each ball 19 will fit into a spiral groove 20 on the outer surface of the section 8 of each 25 carrier. The inner ends of the screws 18 and projections 17 will conform as nearly as possible to the curvature of the bore 9, and it will be obvious that while the ring 16 must rotate with the body 1, the movement of the 30 ring on the body 1 in an axial direction will oscillate the carriers in the bores 9 in one direction or the other. For example, if I move the ring 17 to the left, referring to Fig. 1, the carriers 6 will be rotated in a 35 clockwise direction so as to shift the points of the chasers 10 away from the center of the body 1 and open the die; while, on the other hand, if I move the ring 16 to the right, the carriers will oscillate anticlock- 40 wise, and the die will be closed.

In order to effect this sliding of the ring back and forth on the outside of the body 1, I inclose the ring 16 in a ring 21, which has at one end a flange 22, against which the ring 16 abuts. The opposite end of the ring 22 is internally threaded to receive an annular locking nut 23. The ring 21 will not rotate with the ring 16, and there will be 45 sufficient space between the flange 22 and the nut 23 to allow the ring 16 free rotatory movement. On the outside of the ring 21 are threads 24, which are engaged by another ring 25. The ring 21 is adjustable in the ring 25, and it will now be obvious that if the ring 25 is held stationary, the rotation of the ring 21, because of the screw threads thereon, engaged by the ring 25, will cause the ring 16 to be shifted toward the back or front of the body 1 without in 50 any way interrupting or interfering with the rotation of the ring 16. Of course, the inside of the ring 21, except for the threads for the nut 23 and the inside of the nut 23, is smooth, and not only the ring 16, but the 55 body 1 also, can rotate therein freely.

To support the rings 21 and 25, I provide trunnions 26 on opposite sides of the ring 25, to be received in suitable bearers at the upper ends of pivoted curved arms 27. Each of these arms 27 has a journal or trunnion 70 28, so that it may be mounted in a suitable bearing on the frame 4. The bearings for the trunnion 28, as shown in Fig. 2, will be in alinement and the arms 27 will have extensions 29 which can be bolted or otherwise secured together. These arms 27, with their extensions 29, will be so shaped that when the extensions are bolted together, the arms and the extensions will make a yoke, 75 oscillatably mounted on the frame 4 and oscillatably supporting the ring 25 and ring 21 by virtue of the bearing engagement of the arms 27 at their upper ends with the trunnions 26.

The extensions 29 have alined openings 30, 80 through which passes a spindle 31. These openings are elongated horizontally, and below the spindle 31 are alined openings 32, which are elongated vertically to receive the pin 33 of a crank 34, and which is rigidly 85 mounted upon the spindle 31. The spindle 31 also has rigidly secured thereto at one end thereof a lever 35, and it will now be seen that when the lever 35 is moved back and forth, the crank will shift the lower end of 90 the yoke and thus move the rings 25, 21 and 16 back and forth with respect to the body 1.

The utility of as much of my construction as I have described will now be explained. The die can be opened by moving the lever 100 35 to the left, referring to Fig. 1, whereby the yoke will shift the ring 25 to the left also oscillating the carriers 6 simultaneously in a clockwise direction to throw the points of the chasers away from the center of the 105 body 1. To close the die by moving the points of the chasers back toward the center, the lever 35 is pulled to the right, when the ring 21 is in such position with respect to the ring 25, that the movement of the 110 lever 35 to the right as far as it will go will cause the balls 19 to be located at the ends of the grooves 20, which are nearest to the grooves 11, the size of the die will be as small as it can be made when the chasers 115 are in any given position. To make the die larger, the ring 21 is rotated in the ring 25, so as to move the ring 21 and the ring 16 to the left, referring to Fig. 1. This rotation of the ring 21 may be effected by a suitable tool, such as a spanner, engaging holes in the flange 22 of the ring 21, or in any other convenient way, and similar holes will 120 of course be made in the nut 23 so that it can be screwed in or out. The further the ring 21 is turned so as to slide to the left, referring to Fig. 1, the further will the balls 19 be from the inner ends of the grooves 20 when the lever 35 is locked in right hand 125 position. Hence, the amount of counter- 130

- clockwise rotation of the carrier 6 can be less and less with the result that the points of the chasers will come to a stop at greater and greater distances from the center of the body and the size of the die thus increased. 5 Manipulation in the opposite way will of course make the die smaller. The holes in flange 23 are not shown, but may be placed as needed.
- 10 A suitable spring 36 is connected to the lever 35 and the frame 4 in such a way as to tend normally to draw the lever 35 to the left, referring to Fig. 1, and open the die; and I lock the lever so as to hold the die 15 closed against the force of the spring 36 by means of a dog 37, pivoted to the lever, and having a projection 38 which drops into a notch 39 on the frame 4. On the lever 35 being pulled over to the right, this dog will 20 drop into the recess as soon as the carriers have moved the chasers or cutters inward as far as the carriers can be actuated by the balls 19. To release the lever and open the die, I provide a reciprocable rod 40, mounted 25 in suitable bearings on the framework 4, and having a collar 41 provided with a projection having a forward beveled edge. As shown in Fig. 1, the beveled end of this projection will engage the forward beveled end 30 of the dog 37 to lift the same out of the recess 39 when the rod 40 is moved to the left. An adjustable stop 42 may also be mounted on this rod, if desired. A handle or lever, not shown, connected with the rod 40 may 35 be utilized to operate the same.
- In order to be enabled to control further the size of the die and chasers 10, I make the chasers independently adjustable in the carriers 6, while at the same time retaining the 40 advantages and benefits of being able to oscillate the carriers 6 to a greater or less extent, as detailed in the foregoing paragraphs. Each of the carriers 6 has a groove 43 in its outer end, extending across the 45 same from the circumferential edge of the body 41 toward the bore 5, the bores 43 being so arranged that when the carriers 6 are holding the chasers in working or closed position, the longitudinal axis of these 50 grooves will not extend toward the exact center or axis of the die head, but will extend to one side of the same, that is, in a tangential direction with respect to the bore 5. In each of the grooves 43 is fitted 55 a chaser block 44, and these chaser blocks will be secured to the carriers by means of threaded holes 45 in carrier 6 to receive locking screws 46. The chaser blocks 44 will also have longitudinal grooves 47 to receive 60 the chasers or cutters 10. At their outer ends, the walls of the screws 47 will have interrupted threads 48 to receive adjusting screws 49; these screws serving to push the cutters ahead of them. Further, 65 on each side of the groove 47, the chaser blocks 44 will be provided with recesses 50, and in these recesses will be located locking blocks 51, held by screws 52, and each locking block 51 will have a projection 53 to engage the top of the adjacent cutter, 70 and by pressure upon the same, hold it against displacement. There will be two recesses for each block 44, but only one block 51 and screw 52. This block will always be located in the recess which is on the same 75 side of the groove 47 as the longitudinal threads of the chaser in the block 44, and when the chaser is reversed, the locking block and screw will of course be placed in the opposite recess 50.
- As shown in Fig. 3, the bottoms of the grooves 47 in the chaser blocks 44 will be inclined. The bottoms of the grooves 43 in the carriers 6 will be at right angles to the axis of oscillation of the carriers. Hence, 85 the chasers will not be at right angles to the axis of the body 1, but will be inclined thereto at the angle required to cut threads of the desired pitch on the stock when the body 1 is in motion. The locking blocks 51 90 will be at the inner ends of the chaser blocks, referring to the positions which the parts occupy when the chaser blocks are mounted on the outer ends of the carriers in the head 1, and they are of course replaceable at will, 95 according to the character and conditions of work, in order to adjust the chasers 10 in the grooves 47, the locking blocks are loosened and the chasers 10 moved in or out, as far as the screws 49 will permit. The screws 100 52 are then tightened and each chaser will be securely held in whatever position is given it.
- The function, mode of operation and utility of my invention and all its parts can 105 now be readily understood. First, the chasers 10 are individually adjusted and locked in position and then the body 1 can be set into rotation. The inner ends of the chasers 10 engage the stock and cut the same, 110 and the die can be opened or closed at will by manipulating the lever 35 without stopping the rotation of the body 1. Also the size of the die can be changed within the limits determined by the positions of the 115 inner pointed ends of the chasers 10 by manipulating the ring 21 in the manner already outlined, and the opening and closing of the die, as well as the adjusting of the size thereof, can be done, whether the body 120 1 is in motion or at rest. Hence, the die can be made to work upon successive pieces of stock of the same or different sizes, without shutting down the machine. I provide for holding the ring 21 in adjusted position 125 in the ring 25 by providing ring 25 with a slot 54, extending over a certain length of arc and the ring 25 is provided with a screw threaded opening in the slotted portion to receive a locking screw 55. In or- 130

der to adjust the ring 21, whether the body 1 is rotating or not, the locking screw 55 is turned back, easing the engagement between the threads on the inside of the ring 25 and the threads 24. After the ring 21 is rotated, the locking screw 55 is then turned up to hold the ring 21 in adjusted position. This changing of the size of the die without stopping the rotation of the body 1 is a very important feature of my invention.

I prefer to provide the extensions 7 with central bosses 56 to engage bores in the ends of the sections 8, whereby the extensions 7 and sections 8 can be readily fitted into alignment. Bolts 57 hold the extensions 7 and sections 8 together, and these bolts may be locked by means of screws 58, passing into threaded openings 59, which extend 20 into the sections 8 in a chordal direction. This engagement will hold the parts composing the carriers 6 together against any possibility of their becoming loose in operation.

25 The above construction is intended to operate by causing the body 1 to rotate in a counterclockwise or left handed direction, referring to Fig. 2. In order to adapt my invention so that it can be made to operate 30 with the body 1 rotating in either direction, I simply provide two spiral grooves 20 on the section 8 of the carrier, as shown in Fig. 6. To change from right hand work to left hand work then, or vice versa, I turn out the 35 screws 46 so that the chaser blocks 44 can be pulled backward. I next loosen the locking blocks 51 and the screws 52 so that these locking blocks can be shifted into the recesses 50 on the opposite sides of the 40 grooves 47. The chaser 10 can thus be reversed, and by turning back the screws 13 and 18, the carrier can be pulled out so as to enable the workman to place the other grooves 20 of each carrier into operative relation with the balls 19. This change can 45 be made in a very short time, and eliminates the use or the necessity of different chaser blocks and carriers for right and left hand work.

50 It will be seen with reference to Fig. 2 that the operation of removing the carriers from the bores 9 while the lever 35 and ring 16 are held fast, will cause these carriers to oscillate as they are pulled out, in the same 55 direction as when the lever 35 is moved to open the die. Hence, the advisability of first withdrawing the chaser blocks 44, in order to prevent the ends of the chasers from binding against an adjacent carrier. 60 I may cut away portions of the carriers 6 adjacent the inner ends of the grooves 43, as shown at 60, so as to give sufficient clearance to the working ends of the chasers 10, when the carriers are oscillated in the bores 65 9 to open the die or close it. Of course, to

reverse working, body 1 must be stopped in order to allow the carriers 6 to be shifted, as just described.

In Figs. 6 and 7, I show a modified form of chaser carrier which is the same in some parts as the carrier or holder shown in my Patent No. 1,080,565, granted to me on December 9, 1913. In this form, the section 8 is the same as the section 8 in the form already described, and is joined to the section 7 in the same way, and the groove 11 may extend all around the extension 7 or only half around this extension, as actually illustrated. The portion beyond the extension or section 7, forming the outer end of the carrier, is in the form of a transversely extending projection having one end flush with the end of the extension 7 and the other end located beyond the opposite edge of this extension. I have indicated the projection in question by the numeral 6', in Figs. 6 and 7. To the side of this projection, I secure a swivel plate 61, which is held pivotally in place by means of the bolt 62, and one face of this swivel plate, that is, the face turned away from the projection 6', will have transverse teeth thereon to engage similar teeth in one side of the chaser or cutter 10. The rear end of the chaser is held down by the block 63, which has an overhanging portion 95 through which are passed one or more screws 64 to engage the outer face of the chaser 10. The block 63 is also provided with screw threaded openings to receive a pair of adjusting screws 65, which engage the end of the chaser to adjust the same in a longitudinal direction. It will be apparent that if the screws 64 are loosened and the screws 65 then turned up, that the chaser 10 can be forced to the right, referring to 100 Fig. 7.

As above stated, the swivel plate 61 is pivoted on the bolt 62. Adjacent the opposite end of this plate is a bolt 66, which passes through the block 63, the plate 61 110 and the projection 6' together, and I may make the bore of this bolt through the projection 6' of enlarged dimensions, so as to permit some play of the bolt therein, and thereby allow the plate 61 and the chaser to be swung about the pivot bolt 62 a certain degree. In this way, the chaser 10 can be set for the required pitch on the stock or adjusted so that its length makes any desired angle with the direction of the axis of the carrier 6. As indicated in Fig. 7, the face of the block 63 which engages the plate 61 is provided with teeth to engage the teeth thereon, the same as the chaser 10; and the bolt 66 serves to hold the block 63 and plate 115 61 together so as to secure the chaser 10 while at the same time permitting movement of the plate around the bolt 62. This form of carrier or holder affords various adjustments of the chaser with respect to the axis 120 125 130

5 of oscillation of the holder, and is superior to the form of holder shown in Fig. 3, in which the inclination of the chaser with respect to the axis of the carrier is fixed according to the slope of the bottom of the groove 47.

10 To the face of the swivel plate 61, abutting the side of the projection 6', I secure a lug 67, which may project into an elongated opening into the projection 6'. This projection also carries an adjusting screw 68, extending at right angles to the projection 67 and having shoulders to engage the end thereof. By turning the adjusting screw, it will be apparent that the adjacent end of the swivel plate 61 may be moved in either direction on the pivot bolt 62 and the bolt 66 may be loosened before adjusting and tightened afterward to keep all the parts in rigid relation. Gage marks 69 may be placed on the adjacent edges of the projection 6', and swivel plate 61, as shown in Fig. 6, to indicate the degree of adjustment made.

15 This form of holder or carrier is of course adapted to be used with the body 1 and the other elements of my invention the same as the form shown in Fig. 3. It is just as well adapted for all kinds of work and affords the additional advantage for use in cutting 20 threads on a bolt or screw, and of being adaptable to different pitches of thread. Of course, the form of carrier shown in Fig. 3 will have two threads and two grooves 20 thereon, extending in opposite directions so as to be adapted for both right and left hand work, the same as the form of carrier shown in Fig. 6.

25 The above disclosure is illustrative only, and it is obvious that many changes in the 40 details can be adopted to secure the same advantages and results without departing from the nature of my invention. I therefore wish to reserve to myself the right to make such changes in the shape, size or arrangement of the various parts as fairly fall within the scope and spirit of the claims appended hereto.

30 Having described my invention, what I believe to be new and desire to secure by Letters Patent of the United States is:

35 1. The combination of a movable body, means for carrying one or more chasers supported by the body, said body and said carrying means being shaped to engage each other interchangeably for operation in opposite directions, whereby the same carrying means can be employed, regardless of the direction of operation of the body.

40 2. In a construction of the kind described, a chaser carrier having means for receiving and holding a chaser, and a cylindrical section having a pair of spiral grooves extending in opposite directions in its circumferential surface.

45 3. The combination of a body having a

bore, a chaser carrier having means for receiving and holding a chaser, and a cylindrical portion to be received in said bore, said portion being detachable, means for securing the said portion to the carrier and 70 means for locking the securing means.

4. In a construction of the kind described, the combination of a chaser block having a longitudinal groove therein, said groove having an inclined bottom, a chaser in said groove, the opposite walls of said groove having interrupted threads thereon, an adjusting screw engaging said threads, said block having recesses on either side of said groove, a locking block to fit into either recess to engage the chaser and means for securing said block to the chaser block.

5. In a construction of the kind described, a chaser carrier having a transverse projection at one end, a swivel plate, means for pivotingly securing the swivel plate to one side of the projection, said swivel plate having transversely extending teeth, a chaser having teeth on one side to engage the teeth of the swivel plate, means for adjustably securing the chaser to the swivel plate, and means carried by the projection for adjusting the swivel plate around the means for pivotingly securing the plate to the projection.

6. The combination of a rotatable body having a central opening, and having a plurality of bores extending parallel with said opening and arranged at equal intervals around the same, a chaser carrier, oscillatably mounted in each of said last named bores, said body having longitudinal slots in its circumferential face, forming lateral openings leading to said bores, a ring encircling the body and having projections extending into said slots, said projections carrying means for engaging and oscillating the chaser carriers, a ring receiving the first ring and permitting the first ring to rotate therein, a third ring encircling the last named ring and having threaded engagement therewith, said last named ring having a pair of trunnions, a pivotally mounted yoke receiving said trunnions, and connections for operating said yoke.

7. The combination of a rotatable body having a central aperture, bores extending parallel to said aperture, and spaced equidistant around the same, a chaser carrier oscillatably mounted in each bore of said body, said body having axially extending slots in its circumferential surface forming openings leading to said bores, a ring encircling the body and rotatable therewith, said ring having projections engaging the 120 slots, means carried by the projections to oscillate said carriers, a second ring receiving the first ring and permitting the first ring to rotate therein, said second ring having exterior threads thereon, a third ring 130

engaging said threads and having a slotted portion, a locking screw carried by said slotted portion to secure the second and third rings rigidly together, said third ring having a pair of trunnions, a pivoted yoke for engaging said trunnions and connections for actuating the yoke.

8. The combination of a rotatable body having a central aperture, bores extending parallel to said aperture, and spaced equidistant around the same, a chaser carrier oscillatably mounted in each bore of said body, said body having axially extending slots in its circumferential surface forming openings leading to said bores, a ring encircling the body and rotatable therewith, said ring having projections engaging the slots, means carried by the projections to oscillate said carriers, a second ring receiving the first ring and permitting the first ring to rotate therein, said second ring having exterior threads thereon, a third ring engaging said threads and having a slotted portion, a locking screw carried by said slotted portion to secure the second and third rings rigidly together, said third ring

having a pair of trunnions, a pivoted yoke for engaging said trunnions and connections for actuating the yoke, said connections comprising a lever, a locking dog therefor, and movable means comprising an element having a beveled end to engage the dog and release the lever.

9. The combination of a die head, one or more chaser carriers mounted therein, means encircling said die head, and engaging said carriers to adjust the same, means encircling the first means and rotatable with respect thereto to operate the first means, and an element encircling said last named means to actuate the same, said element and said last named means being adjustable axially of the die head with respect to each other.

In testimony whereof, I have signed my name to this specification in the presence of two subscribing witnesses, this nineteenth day of November, 1914.

VICTOR R. KOONTZ.
